JOHN P. SHAMBERGER, OF BALTIMORE, MARYLAND.

STEM AND BIT LOCKING DEVICE.

1,390,931.

Specification of Letters Patent. Patented Sept. 13, 1921.

Application filed October 21, 1919. Serial No. 332,136.

To all whom it may concern:

Be it known that I, JOHN P. SHAMBERGER, a citizen of the United States, residing at Baltimore, in the county of Baltimore and 5 State of Maryland, have invented new and useful Improvements in Stem and Bit Locking Devices, of which the following is a specification.

The invention relates to well drilling tools 10 and has for an object to provide a lock for use in locking the bit to the stem of a well drilling tool.

Among other features the invention comprehends a lock of simple construction and 15 which is so arranged as to permit of the ready connection of a bit with the stem and the locking thereof to the stem, also providing for the ready unlocking of the bit from the stem and its subsequent removal therefrom so that with the use of the lock to be 20 described, the bit cannot accidentally remove itself from the stem while in use.

In the further disclosure of the invention reference is to be had to the accompanying 25 drawings, constituting a part of this specification, in which similar characters of reference denote corresponding parts in all the views, and in which,—

Figure 1 is a fragmentary elevation of a 30 stem and the bit thereof, showing the latter locked to the stem.

Fig. 2 is a similar view with the locking pin or bar in unlocked position and the bit in the process of removal from the stem.

Fig. 3 is a vertical longitudinal sectional view taken on the line 3—3 in Fig. 1, and 35 Fig. 4 is a horizontal sectional view taken substantially on the line 4—4 in Fig. 3.

Referring more particularly to the views, 40 the numeral 10 indicates a stem and the numeral 11, a bit, the latter having a threaded tapered shank 12 for threaded engagement with the stem 10 as shown, the formation of the shank 12 on the bit 11, providing 45 a ledge or surface 13 which abuts against an end 14 of the stem when the bit is applied.

A longitudinal bore or opening 15 is 50 formed in the stem 10 immediately adjacent the periphery 16 thereof, thus providing an intermediate wall 17 and disposed in this opening 15 is an expansible helical spring 18, the lower end of which abuts against a locking bar or pin 19 arranged to slide in the opening 15. The bit 11 is similarly 55 formed with a bore or opening 20, the bottom 21 of which has a cross groove 22 there-

in and the outer wall 23 of the opening 20, is formed with a vertical slot 24, the lower end of which at 25 communicates with the cross groove 22 and is in fact a part thereof. The 60 wall 17 is also formed with a longitudinal slot 26 which is adapted to register with the slot 24 when the bit is screwed into the stem and the slot 26 terminates at its upper end in a cross portion 27 the bottom of 65 which is formed with notches 28 defining retaining lugs 29 in the wall 17. A projection or pin 30 is provided on the locking bar 19 and operates in the slots 24, 26, and the cross portion 27. 70

Now it will be apparent that when the locking bar 19 is raised against the action of the spring 18 so that the lower part of the locking bar will lie within the opening 15 and above the horizontal plane of the 75 ledge or surface 13, the bit will be in unlocked relation relative to the stem, the locking bar 19 having been slightly rotated when moved upwardly so as to bring the projection or pin 30 out of the slot 26 and 80 into one of the cut out portions 28 to rest against and be held by one of the side lugs 29 against the downward action of the spring. The bit can now be readily disengaged from the stem and when at a subsequent 85 time it is desired to secure the bit to the stem and lock it in position so as to prevent accidental removal of the bit when the drilling tool is in use, the bit is first threaded into the stem in the usual manner 90 to bring the slots 24, 26, into registration thus also bringing the openings 15, 20, into registration. The projection or lug 30 is now moved out from the cut out portions 28 in which it has been reposing and is 95 brought into alignment with the slot 26 and then released, thereby permitting the spring 18 to act and force the locking bar downwardly into the opening 20 to the bottom 21 thereof, thus bringing the projection or lug 100 30 into the slot 24. It will be apparent that the projection or lug 30, because of the engagement of the locking bar 19 with the bottom 21 of the opening 20, will not lie in the lowermost portion of the slot 24 so that 105 the lower portion 25 of the slot will be free and open, permitting of the insertion of a nail or other similar implement into the lower portion 25 of the slot and into the groove 22, to engage against the underside 110 of the locking bar 19 so as to permit of raising the same against the action of the

spring when it is again desired to unlock the bit relative to the stem.

I preferably dispose the lock described, adjacent the peripheries of the stem and bit so as to obtain the greatest locking action and prevent a shearing of the locking bar when it is in locked position, although if the locking bar is made sufficiently large, this would hardly be possible, unless an exceptional torsion were exerted on the bit. It will be apparent however that with my form of device no part of the lock comprising the bar, the spring and the projection or lug, extends beyond the peripheries of the stem or bit and no interference with the threaded connection between the stem and bit results in having the lock disposed in the particular manner mentioned.

Although I am aware that ordinarily a bit threaded into the stem of a well drilling tool is partially prevented from disengagement thereof by reason of the friction between the threads in contact with each other and the friction between the shoulder or end of the stem and the shoulder or flange 13 of the bit, I have found that in actual use this friction is not always sufficient to maintain the bit and stem in proper thread-

ed engagement and that the provision of an additional locking element is necessary 30 and it is for this reason that I have provided the simple and effective lock described and shown herein.

Having described my invention, I claim,—

A lock for the bit and stem of a well 35 drilling tool, each of which is provided with a cylindrical recess, the bit being formed with a longitudinal slot communicating with the recess therein and the stem being formed with a T-shaped slot communicating with the recess therein, the bottom wall of the transverse portion of said T-shaped slot being formed at opposite sides of the shank portion with notches, both of said slots being adapted to be brought into registration 40 when the stem and bit are assembled, a longitudinally disposed spring-pressed plunger 45 slidable and rotatable within the recess in the stem, and a pin projecting laterally from said plunger and movable along the 50 registering slots, the pin being engagable within either of said notches whereby to hold the plunger in retracted position out of engagement with the recess in the bit.

In testimony whereof I affix my signature. 55
JOHN P. SHAMBERGER.
